UNITED STATES PATENT OFFICE.

JOHN DRAHER AND ADOLPH J. KRIEGER, OF WATERBURY, CONNECTICUT.

MEANS FOR SETTING MEMBERS OF SEPARABLE FASTENERS.

Application filed February 4, 1927. Serial No. 165,823.

This invention relates to improvement in means for setting members of separable fasteners, that is, fasteners which comprise complementary members arranged on strips of flexible material and adapted to be interlocked. The more customary way of applying these fastener members is to place them, one at a time, on a strip, and by means of a press crowd the gripping-edges together, but this is a slow process, and the members are not always regularly arranged, so that those on one side will not register with the complementary members on the other side. The object of this invention is to provide means whereby as many members as are required for a single strip can be fixed to the strip at a single operation, and the invention consists in the construction as hereinafter described and particularly recited in the claims.

In the accompanying drawings:

Fig. 1 is a front view of a machine for setting separable fasteners, constructed in accordance with our invention;

Fig. 2 is a broken side view of the same;

Fig. 3 is a sectional view, showing the parts in position before the closing operation takes place;

Fig. 4 is a similar view, showing the closing operation completed;

Fig. 5 is a plan view of the bracket and yoke mounted therein; and

Fig. 6 is a top view of the plates.

In carrying out our invention, we employ two holding-plates 10 and 11. These plates are connected together and, as herein shown, by means of couplers 12 and 13, the lower plate 11 being rigidly secured to the couplers 12 and 13, and the upper plate 10 is provided with studs 14 to enter holes 15 formed for them in the couplers 12 and 13, but it is obvious that these plates might be otherwise connected together, so that one may turn with relation to the other. The adjacent faces of these plates are formed with a series of grooves 16 and 17 to receive fastener-members 18, which may be of any approved construction, but which have gripping-jaws 19 and 20. The lower plate 11 is located in a groove 21 formed in a die-block 22, which is located on the die-bed 23 of a press in line with the usual ram 24, but it is obvious, without illustration, that the plate 11 might be secured in any desired manner directly to the die-bed 23. Se-

cured to the ram to move therewith is a bracket 25, and pivotally connected with the bracket is a yoke 26 carrying a long pusher or comb 27. A spring 34 is located between the yoke and bracket. The pivot 28 on which the yoke is mounted extends through a slot 29 in the bracket, so that it has a certain amount of rocking movement, independent of the bracket, and mounted in the bracket and bearing upon the pivot 28 is a spring 30 tensioned by a screw-plug 31. Stop-pins 32 are mounted in the bracket to limit the swinging movement of the yoke. Separable fasteners 18 are placed between the plates and the plates then located beneath the ram and a strip of fabric 33, to which the fasteners are to be applied, is placed beneath the comb 27. As the ram descends, the comb moves toward the plates 10 and 11 and forces the strip 33 between the jaws 19 and 20 of the fasteners. Then, as the ram continues its downward movement, it strikes the plate 10 and rocks it so that the forward edge comes down and presses the jaws into engagement with the edge of the fabric-strip. By providing the spring 30 and the slots 29, the yoke 26 will yield against the tension of the spring 30 and thus not interfere with the final downward movement of the ram.

With this mechanism, all of the fasteners for a single strip are applied at one movement of the ram, and the fastener members are attached to the fabric-strip and regularly spaced. As many pairs of plates 10 and 11 as may be required can be used, and these plates filled with fastener members and passed to the operator of the press.

We claim:

1. Means for setting members of separable fasteners, consisting of two plates, one hinged with relation to the other, the adjacent faces of the plates formed with fastener-receiving grooves, a ram adapted to force the plates together, and means moved by the ram for inserting a strip of fabric between the gripping-jaws of the fastener members.

2. Means for setting members of separable fasteners, comprising two plates, one arranged above the other and one movable with relation to the other, the adjacent faces of said plates formed with fastener-member grooves, a ram adapted to force the two plates together, a yoke moved by said ram,

and a comb mounted on said yoke, whereby a strip of fabric is inserted between the plates in advance of the closing movement thereof.

- 5 3. Means for setting members of separable fasteners, comprising two plates, one arranged above the other and one movable with relation to the other, the adjacent faces of said plates formed with fastener-member grooves, a ram adapted to force the two plates together, brackets connected with said ram, a yoke yieldingly mounted in said brackets, and a comb carried by said yoke, whereby a strip of fabric is inserted between the plates in advance of the closing movement thereof.
- 10 4. Means for setting members of separable
- 15

fasteners, comprising two plates, one arranged above the other and one movable with relation to the other, the adjacent faces of said plates formed with fastener-member 20 grooves, a ram adapted to force the two plates together, brackets connected with said ram, a yoke yieldingly mounted in said brackets, and a comb carried by said yoke, whereby a strip of fabric is inserted between 25 the plates in advance of the closing movement thereof.

In testimony whereof, we have signed this specification.

JOHN DRAHER.
ADOLPH J. KRIEGER.
